UNITED STATES PATENT OFFICE.

MATTHEW WIARD AND CHARLES C. PETTIT, OF PHILADELPHIA, PA.

DESIGN FOR STALL-GUARDS.

Specification forming part of Design No. **11,225**, dated June 3, 1879; application filed April 21, 1879.
[Term of patent 3½ years.]

To all whom it may concern:

Be it known that we, MATTHEW WIARD and CHARLES COOPER PETTIT, both of Philadelphia, in the county of Philadelphia and State of Pennsylvania, have invented an Improved Design for Stall-Guards, of which the following is a specification.

Our invention relates to that class of stable-castings known as "stall-guards," and which are designed to prevent horses biting each other; and consists in constructing a stall-guard of such a design that the shape commonly given to castings for this purpose is entirely dispensed with, and one of more beauty, symmetry, and strength substituted.

The curves of the ordinary guards are changed to straight lines, and the ornamental work forming the body of the guard is such that it corresponds to the outline of casting, and is so shaped in cross-section that it imparts great strength to the entire guard.

Figure 1 is a side elevation of our improved design for stall-guards. Fig. 2 is a cross-section of same through the line X X.

A B C D E F G H S T represent what might be and will be called the "frame" of the guard, and really forms two parts to same, respectively I and J. The parts I and J are entirely filled with a diamond-shaped ornamentation, which is composed of a thin casting, K, perforated at equal distances with diamond-shaped openings M M, and which is strengthened by the oblique ribs L L and a rib, N, which entirely incloses the ribbed diamond-shaped ornamentation. Between this rib N and the frame A B C D E F G H S T is a narrow plate, K', of casting of equal width. These ribs L L and N and the frame insure great lateral strength to the plate K K', and hence the guard as a whole. This ribbed diamond-shaped ornamentation on stable-castings is used by us exclusively, so far as we are aware.

Upon the sides A and B are lugs O O,

through which screws are put to secure the guard to the stall-planking. The angle formed by the sides F and G is filled in by the parts P, which is composed of a rib, p, and plate p'. The angle given to the sides D, F, and G is dependent on the shape of the diamond openings M M, or vice versa.

An important part of our design is that there is no segment or portion of a diamond, but halves and whole diamonds, which insure great strength to the casting, while in the common shape of guards the curves given to them cut up the ornamentation into all conceivable forms and sizes, thereby giving unevenness in the distribution of metal, and a corresponding loss in strength.

Between the sides G and H is a small part, R, bounded by sides S and T.

We do not consider that our design would be altered by dispensing with the small part R, by continuing the side G until it meets side H, or even by taking away the small part T, since our design is included in making a guard of a frame composed of straight lines, as shown in the drawings, and an ornamentation composed of ribbed diamond-shaped orifices M M in plate K K' and ribs L L N, yet we prefer to use parts J and R in constructing our stall-guard.

There is no expensive finishing, as drilling, on our guard.

We claim—

In design, a stall-guard constructed of straight bounding sides, and ribbed diamond-shaped ornamentations within said sides, substantially as described, and for the purpose specified.

In testimony of which invention we hereunto set our hands.

MATTHEW WIARD.
CHARLES C. PETTIT.
